PISTOL

Robert L. Hillberg, West Cheshire, Conn.

Application April 30, 1954, Serial No. 30,261

Term of patent 14 years

(Cl. D30—1)

Fig. 1.

Fig. 2.

Fig. 3.

Fig. 4.

Fig. 5.

Fig. 6.

Fig. 1 is a side elevational view of a pistol embodying my new design;

Fig. 2 is a similar view showing the other side of the pistol;

Fig. 3 is a top plan view;

Fig. 4 is a bottom plan view;

Fig. 5 is a front elevational view; and

Fig. 6 is a rear elevational view of the pistol.

I claim:

The ornamental design for a pistol, substantially as shown.
